UNITED STATES PATENT OFFICE

FRED HIMMEL AND ISIDORE HIMMEL, OF NEW HAVEN, CONNECTICUT, ASSIGNEES TO
THE HIMMEL BROTHERS COMPANY, OF NEW HAVEN, CONNECTICUT, A CORPORA-
TION

STORE FRONT CONSTRUCTION

Application filed January 7, 1932. Serial No. 585,289.

This invention relates to an improvement in store-front constructions and particularly to means for supporting a sheet of glass between inner and outer members. In supporting large sheets of glass, the inner and outer strips must have sufficient strength to withstand the strain imposed by the pressure of the glass inward and outward.

The object of this invention is to provide means connected with the inner and outer strips for reinforcing and supporting the same, and the invention consists in the construction as hereinafter described and particularly recited in the claims, and is an improvement on the construction shown and described in United States Patent No. 1,849,525, granted on our application.

In the accompanying drawing:

Fig. 1 is the front view of a store-front construction illustrating our invention;

Fig. 2 is an end view of the same;

Fig. 3 is a sectional view on the line 3—3 of Fig. 1;

Fig. 4 is a sectional view on the line 4—4 of Fig. 3;

Fig. 5 is a sectional view on the line 5—5 of Fig. 3;

Fig. 6 is a perspective view of the mounting-block, detached;

Fig. 7 is a perspective view of the front-strip supporting-member, detached; and

Fig. 8 is a perspective view of the rocker, detached.

In carrying out our invention, we employ inner strips 10 and outer strips 11, which may be formed from sheet-metal or extruded metal. Connected with the inner member is a series of mounting-blocks 12, only one being shown. This consists of a base 13 formed at its forward side with perforated lugs 14 and rearwardly-projecting shoulders 15. Above the base is a horizontal shelf 16 and above this is a head 17, the head and shelf being formed with threaded perforations 18 and 19 arranged in a line at an angle to the perpendicular.

Mounted in the lugs 14 is a rocker 20, formed in rear of its pivotal point with a yoke 21 and forward of the pivotal point with a rounded finger 22. This rocker is

mounted in the inner strip with which it is interlocked by upwardly-struck lugs 23 from the base 24 of the inner strip, to enter notches 25 formed in the base of the mounting-block which is held against lateral movement by lugs 26 also struck upward from the base 24.

Before the block is engaged with the inner strip, a screw 27 is inserted upward through the hole 19 in the shelf and the hole 18 in the head, the upper end of the screw being nicked and exposed through the upper end of the inner member. The lower end of the screw is formed with spaced flanges 28 and 29 between which the yoke 21 extends, and so that movement of the screw will turn the rocker.

By having the screw extend through the head and shelf, it is firmly supported. In the outer strip 30 is a supported-member 31, preferably of extruded metal and of a length to enter a socket 32, formed by turning the upper end 33 of the strip downward. The lower end of this member is inclined downward and terminates in lugs 34 which are interlocked with the base 35 of the front-member by turning a finger 36 upward therefrom.

Projecting inward from the inner wall of this member is a plate 37 positioned to extend beneath the shelf 16. Projecting downward and rearward from the under-face of the plate is a cam-extension 38 with the forward face of which the finger 22 of the rocker will engage, and so that when the screw is turned downward, the rocker engaging with the cam 38 will draw the outer member toward the inner member and so clamp a sheet of glass 39 between them, the sheet being supported by the shelf 16 and resting upon a strip of padding 40 of any suitable material.

With the parts assembled as described, downward movement, as before stated, turns the rocker 20, which draws the outer member rearward, the plate 37 sliding against the underface of the shelf 16 by which it is guided, and thus a very rigid construction is provided, and the construction may be installed with great facility.

We claim:

1. In a store-front construction, the combination with inner and outer strips thereof,

of a mounting-block connected with the inner strip, said mounting-block comprising a head, a shelf and perforated lugs below the shelf, the head and shelf formed with aligned threaded openings, a screw extending through said openings, a rocker pivotally mounted between said lugs and connected with said screw, a supporting-member connected with the outer strip and formed with a rearwardly-projecting plate adapted to engage with the under-surface of said shelf, and with a cam-surface adapted to be engaged by said rocker.

2. In a store-front construction, the combination with inner and outer strips thereof, of a mounting-block comprising a head, a shelf and perforated lugs below the shelf, the head and shelf formed with aligned threaded openings, a screw extending through said openings, a rocker pivotally mounted between said lugs and connected with said screw, a supporting-member connected with the outer strip and formed with a rearwardly-projecting plate adapted to engage with the under-surface of said shelf and with a cam-surface adapted to be engaged by said rocker, and means for interlocking the mounting-block and outer supporting-member with their respective strips.

3. In a store-front construction, the combination with inner and outer strips thereof, of a mounting-block connected with the inner strip, said mounting-block comprising a head and a shelf, and perforated lugs below the shelf, the head and shelf formed with threaded openings aligned at an angle to the perpendicular, a screw extending upward through said openings, a rocker pivotally mounted between said lugs, a supporting-member connected with the outer strip and formed with a rearwardly-projecting plate adapted to engage with the under-surface of said shelf, and with a cam-surface adapted to be engaged by said rocker.

In testimony whereof, we have signed this specification.

FRED HIMMEL.
ISIDORE HIMMEL.
